UNITED STATES PATENT OFFICE.

MORRIS S. WRIGHT, OF WORCESTER, MASSACHUSETTS.

AUTOMATIC MUSICAL INSTRUMENT.

SPECIFICATION forming part of Letters Patent No. 638,615, dated December 5, 1899.

Application filed October 15, 1898. Serial No. 693,588. (No model.)

To all whom it may concern:

Be it known that I, MORRIS S. WRIGHT, of the city and county of Worcester, in the State of Massachusetts, have invented certain new and useful Improvements in Automatic Musical Instruments; and I do hereby declare that the following is a full, clear, and exact description thereof, reference being had to the accompanying drawings, forming a part of this specification, and in which—

Figure 1 represents a vertical transverse section through so much of an automatic reed instrument as is necessary to illustrate my invention, the usual keys and connections also being shown applied thereto in connection with the automatic mechanism of said instrument. Fig. 2 is an enlarged front view of part of the music-box and mechanism for operating its rolls. Fig. 3 is an enlarged view of part of the vertical section shown in Fig. 1, all the following figures also being upon an enlarged scale. Fig. 4 is a horizontal section through part of the secondary channel-board, taken on line *a*, Fig. 3, showing a top view of part of one of the tone-chambers, its channel-board, and pneumatic cut-off valves. Fig. 5 is a vertical longitudinal section through the secondary channel-board, taken on line *b*, Fig. 3, looking in the direction indicated by the arrow. Fig. 6 is a vertical longitudinal section through part of the primary channel-board or "tracker-board," taken on line *c*, Fig. 3, showing a front view of some of the primary pneumatics beyond. Fig. 7 is a horizontal section through part of the secondary channel-board, taken on line *d*, Fig. 3, and showing a plan of part of the tracker-board and primary pneumatics. Figs. 8 and 9 are vertical longitudinal sections through the parts shown in Fig. 3, taken on lines *e* and *f*, respectively, showing front views of portions of the instrument, which will be hereinafter described. Figs. 10 and 11 are horizontal sections taken on lines *g* *h*, respectively, Fig. 3, looking down and showing the parts beneath in plan view. Fig. 12 is an enlarged detached plan view of one of the channeled blocks of the tracker-board under each pair of primary pneumatics, showing also a plan of the hinged cut-off valve arranged and secured thereon, as and for the purpose hereinafter more fully described; and Fig. 13 is a central vertical

longitudinal section of said parts shown in Fig. 12.

My invention relates to reed instruments, and more especially to automatic reed instruments in which perforated sheet-music is used for producing the different tones of a tune played thereon. It may also in practice have combined therewith the usual keys and connections for operating the instrument by hand and may, furthermore, if desired, be connected, by means of suitable mechanism, with one or more key or string instruments combined with the automatic part of the instrument. Said connections not constituting a part of this invention, it will be unnecessary to illustrate or describe the same.

The object of my invention is to increase the capacity of the above class of instruments without materially enlarging the same over their usual size or of widening the perforated sheet-music used thereon over its usual width.

Said invention consists of certain improvements in the pneumatic system whereby two primary pneumatics provided with a cut-off valve between them may be operated from one opening and channel in the primary channel-board and also whereby one reed-valve and reed may be operated from said two primary pneumatics, each of said primary pneumatics operating said reed-valve independently. The purpose of said double pneumatics and valve device is to enable one reed-valve and its reed to be operated from two different sizes of openings in the perforated sheet-music, both admitting air into one and the same opening in the primary channel-board and passing through a single channel to said double pneumatics and valve device, the air admitted through the large openings in said sheet-music producing the solo or melody parts of a tune and that admitted through the smaller openings therein the accompaniments thereto, as will be hereinafter more fully set forth.

In order that those skilled in the art to which my invention appertains may better understand the nature and purpose thereof, I will now proceed to describe it more in detail with reference to the accompanying drawings.

In Fig. 1 of the drawings I have shown both a music-box *A* for producing the music automatically and keys *B* for playing said

music by hand in connection with my aforesaid improvements, and I reserve the right to use either separately or both together with said improvements. I also reserve the right 5 to combine such other instruments therewith as are in practice adapted for the purpose of operating in conjunction with the same and coming within the scope of my invention.

As my invention relates principally to automatic musical instruments, as previously stated, I will first describe my improvements as being combined with the music-box A and its appliances. Within said music-box are arranged the usual rolls C C, over which the 15 perforated sheet-music D is passed, the same unrolling from one to the other, as usual, over the mouthpiece E' of the primary channel-board E when the instrument is operated. The mechanism for operating said rolls not 20 constituting a part of my invention, it will be unnecessary to illustrate or describe the same. Said primary channel-board extends from near the glass front A' of the music-box to the principal or secondary channel-board 25 F and is provided with one channel G for each pair of pneumatics H I, said channels terminating at the outer end of the primary channel-board in the openings J at the mouthpiece E'. Said pairs of primary pneumatics 30 are in this instance shown arranged transversely of the instrument; but I do not limit myself thereto. For the purpose of economizing in space each alternate pair of primary pneumatics H I is raised above the level 35 of the others, one pair being level with the top of the primary channel-board and the pair next to it a little above it, and so on through the two rows or series, as is shown in the drawings. By this arrangement I am enabled 40 to place twice the number of pneumatics in about the usual amount of longitudinal space, and thus not necessitating any material additional length in the construction of the instrument.

45 The pneumatics H are operated by the air admitted through the wide openings K in the sheet-music D and the pneumatics I by that admitted through the narrow openings L in said sheet-music, as will be hereinafter more 50 fully described. Said pneumatics H are each connected by the vertical wire stems H' with the cut-off or switch valve H² for closing and opening the air-outlet H³ in the wind-chest M and also with the cut-off or switch valve 55 H⁴ for closing and opening the air outlet or vent in the channel M' of said wind-chest, and the pneumatics I are also connected in the same way by the vertical wire stems I' with the cut-off or switch valves I² I³ for closing 60 and opening the air-outlets I⁴ I⁵ in the wind-chest N and wind-chest channel N', respectively. Each channel M' N' is separately connected with a separate channel O' in the principal or secondary channel-board F, in this instance the channel N' connecting with the channel O and the channel M' with the channel O' of each pair. (See Figs. 4, 5, 7, 10

and 11.) Each pair of channels O O' is in turn connected, by means of the bottom and top double angular channels P' P² in the tone-channel board P, with the space P³ back of each secondary pneumatic Q in tone-chamber R. Therefore, as will be readily seen, each pair of primary pneumatics H I is supplied with air through a single opening J and channel G in the primary channel-board and is also each separately and independently connected, as aforesaid, with each secondary pneumatic Q in the tone-chamber. The purpose of this construction and arrangement is 70 to admit of making the sheet-music with two widths of perforations or openings within the usual space in width of said sheet-music, and thus doubling the capacity of the instrument without, as previously stated, materially adding to the usual length of said instrument. In order to accomplish this result of operating both primary pneumatics of each pair by air admitted through two widths of openings in the sheet-music and conducted through a 80 single opening and passage to both pneumatics, so that one pneumatic will be operated by air admitted through the wide openings in the sheet-music and the other by air admitted through the narrow ones, I have arranged 85 a cut-off valve S under and between the pneumatics of each pair of said primary pneumatics in a chamber S' between the primary channel-board E and a block T, attached to the under side thereof. The chamber S' is connected by a horizontal opening G' with channel G, (see Figs. 1 and 6,) by a top vertical opening G² with the pneumatic H, and with a bottom vertical opening G³ under the inner end of valve S, in turn connected with an angular 90 channel G⁴, connecting with the pneumatic I. The outer end of said valve S is hinged, by means of thin leather or otherwise, to the block T, and its inner end is arranged to tilt 95 up and down to open and close the opening 100 G³. When in its normal position, said inner end of the valve is held elevated above said opening by the weight of pneumatic H through its wire H' resting upon and forcing 105 down the outer end thereof, as is shown in Figs. 1 and 3 and by dotted lines in Fig. 13; but when sufficient air is admitted through the opening in the sheet-music to raise said pneumatic H the inner end of the valve is 110 permitted to drop down by force of gravity over said opening G³ to close the same, as is shown by full lines in Fig. 13, and thus cut off said air from reaching and operating the other pneumatic I, said pneumatic I being 115 operated only when insufficient air is admitted to raise the first pneumatic H. To facilitate said valve closing quickly and tightly 120 over opening G³, it may be provided with a weight S² or other equivalent means for the 125 same purpose.

130 In practice the parts are so constructed and arranged in relation to each other that when a wide opening in the sheet-music arrives over the opening in the mouthpiece E'

- the first pneumatic H is raised with a quick movement and the opening G³ closed to prevent the other pneumatic I being operated, what little air passes under the valve S being permitted to escape through the vent T' and the surplus air under the pneumatic H and in channel G being permitted to escape through the vent T²; but when a narrow opening in the sheet-music arrives over the opening in the mouthpiece E', insufficient air being admitted to lift the first pneumatic H, the valve S is not operated to close opening G³, and consequently said air passes through under pneumatic I and operates it without lifting the other pneumatic H.
- The above result is obtained by the disk of pneumatic H, which may be termed the "high-pressure" pneumatic, being made smaller than that of pneumatic I, which may be termed the "low-pressure" pneumatic. The reason, therefore, is that in practice it is found that the smaller the disk is of a diaphragm-pneumatic having an extremely-flexible covering the less power it has for exerting a pressure to operate the wind-chest valves, and vice versa. Therefore pneumatic H, being the smaller of the two of each pair, will not rise as quickly or forcibly as pneumatic I when the air-pressure is applied to the under side thereof. By reference to Figs. 1 and 3 of the drawings it will be observed that the wind-chest valves H² H⁴, which are operated by the small or high-pressure pneumatic H, are larger than the wind-chest valves I² I⁴, operated by the larger or low-pressure pneumatics I. Consequently the pneumatic having the least power—in this instance pneumatic H—has the most work to do and requires a greater amount of air to operate it. Therefore air is admitted thereto through the large holes in the sheet-music, while, on the other hand, the pneumatic I, having a larger disk than pneumatic H and smaller wind-chest valves than said pneumatic H, as aforesaid, is operated by air admitted through the small openings in said sheet-music. In said construction and operation of the pneumatics and their wind-chest valves the vent-openings T' T² constitute a very essential feature and must be so proportioned to the narrow and wide openings in the sheet-music as to permit the air-pressure in the channels to lift only its respective pneumatic without raising the other—as, for instance, the opening in the vent T² must be so proportioned to the narrow perforations I in the sheet-music that it never permits the pressure in the channel G to reach a lifting power sufficient to elevate pneumatic H.
- Each double channel P' P² has an outlet at the edge of the tone-channel board P, and over said openings are secured the flexible cut-off pneumatic valves V, made of leather or other flexible material. Over said flexible valves V are in turn arranged the long spring cut-off valves W, extending the whole length of each tone-channel board and mechanically

operated by the "stops" of the instrument, as usual, to open and close the connection between the space back of the tone-chamber pneumatics Q and the other channels and chambers between the same and the cut-off valves H² H⁴ and I² I⁴.

It will be understood that in practice the music-box A, wind-chests M N, and tone-chambers R are all supplied with a constant supply of air under equal pressure from the usual bellows or other source of supply during the operation of the instrument. Consequently when the wind-chest valves H² I² and tone-chamber valves W are open an equilibrium of the air-pressure through the various passages being maintained at each side of the secondary pneumatics Q, the latter are held stationary and the reeds X are not operated until one of the pneumatics H or I is operated by one of the openings in the sheet-music coming over one of the openings in the mouthpiece E'. The air thereby admitted then causes one of said pneumatics to be lifted and its valve H² or I² to be forced up to close the wind-chest opening and its valve H⁴ or I⁴ to also be raised to open the vent H⁵ or I⁵, thus permitting the air in the various channels back of said secondary pneumatic Q to escape and allowing the compressed air in the tone-chamber to force them back, thereby in turn causing the reed-valve Y to be drawn back and opened by means of the wire connection Y' and allowing the air to escape therethrough and operate its reed X in reed-board X'.

The tone-chambers R, with the exception of having the top and bottom double channels P' P² and the double cut-off valves thereof previously described, are similar to those shown and described in my United States Patent No. 509,506, dated November 28, 1893, for improvements in reed or pipe organs, said tone-chambers being made removable from the secondary channel-board F and each connected with a separate stop for each valve, or, in other words, each separate tone-chamber being provided with two separate stops instead of one, as usual. The wind-chests are also in this instance made removable and similar to the one shown in said United States patent, being each provided with a double cut-off or switch valve, said cut-off or switch valves being shown connected with the key mechanism in said patent and with the vertical wire stems of the primary pneumatics in the present case, as previously described.

With the foregoing exceptions no claim to novelty is claimed for the tone-chambers and wind-chests, except in combination with the double-primary-pneumatic system supplied with air through one opening and channel, as hereinbefore described, and pointed out in the claims.

Having described my improvements in detail, the operation of an instrument embodying the same may be briefly summed up as follows: Assuming that the air-pressure is ap-

plied, the music-rolls in operation, with the perforated sheet-music passing over the mouthpiece E', and the proper stops are drawn to open the proper cut-off valves W, 5 when a wide opening in said sheet-music arrives over its opening J in said mouthpiece air being admitted therein passes through the single passage or channel in the primary channel-board and striking the under side 10 of its pneumatic H lifts it, and at the same time closing the valve leading to the second pneumatic I prevents the operation thereof. Said pneumatic H being thus lifted raises the cut-off valves H² and H⁴, thereby closing the 15 wind-chest opening H³ and opening the vent H⁵. This permits the secondary pneumatic Q to be depressed or forced back by the air-pressure in the tone-chamber, the reed-valve to be opened, and the air to pass through and 20 operate reed X, the air forced back by said depression of secondary pneumatic Q passing out through said vent H⁵. In playing a tune several wide openings are of course liable to come in succession over the same opening in 25 the mouthpiece E' in producing the solo or melody parts of said tune; but assuming that a narrow opening now follows the wide one to produce the accompaniment to said solo or melody parts, a smaller volume of air being 30 forced through the channel in the primary channel-board and insufficient in power to raise the first pneumatic H of the pair, it passes along without raising said pneumatic or closing the valve S and striking under the 35 second pneumatic I raises it, thereby operating through similar connections as those for pneumatic H, as previously described, the same secondary pneumatic Q, and in consequence the same reed is operated as was operated by the other primary pneumatic of said 40 pair.

Although I have shown and described the instrument as being constructed with two primary pneumatics H I in each set or pair 45 and the sheet-music with two sizes of openings, it is obvious that it may in practice be made and adapted for three or more primary pneumatics and sizes of openings without departing from the principle of my invention, 50 and I therefore do not limit myself to the number herein shown and described. I also reserve the right in practice of operating the instrument by air-suction instead of air-pressure, as herein described. Both are applicable to my invention; but the pressure system is preferable.

By the foregoing construction of employing high and low pressure pneumatics operated from a single opening and channel in the primary channel-board the high-pressure pneumatic may be connected with one kind of instrument and the low-pressure pneumatic with another kind of instrument. Therefore if the perforations in the sheet-music are properly arranged a similar effect may be produced to that of two persons playing on different instruments. One or the other of said high and

low pressure pneumatics may be connected with and played from the usual keys, as shown in the drawings, as well as automatically, as 70 hereinbefore described. Only one bank of keys B and connections are in this instance shown in the drawings; but it is obvious that two or more banks and their connections might be used, according to the number of 75 pneumatics employed in each transverse set. Said key connection is made by extending the primary channel-board G down, as shown at G⁴, and connected with the usual wind-chest and valve device Z. As the key connections with 80 said wind-chest are of old construction and well understood, the illustration thereof in Fig. 1 will be sufficient to fully explain the same without further description. The mechanism for connecting the stops Z' Z' with the 85 valves W is also old and well understood, and as the same constitutes no part of my invention it is deemed unnecessary to illustrate or describe the same.

Having now described my invention, what 90 I claim as new, and desire to secure by Letters Patent, is—

1. Perforated sheet-music for automatic musical instruments, consisting of a single sheet of suitable material, having different 95 widths, sizes and shapes of openings formed therein according to the tune to be played, in combination with the primary channel-board, having an opening and channel for each pair of primary pneumatics; the series 100 of primary pneumatics, mounted on said channel-board; a cut-off valve, arranged between the pneumatics of each pair; a double wind-chest, provided with separate channels and double, cut-off or switch valves, two of each 105 for each pair of primary pneumatics, and said valves, separately connected with said primary pneumatics; a secondary channel-board, provided with two channels for each pair of wind-chest channels, each separately connected with said wind-chest channels, and a tone-chamber, containing a series of separate, 110 secondary pneumatics and reed-valves, one of each for each primary channel and reed, substantially as and for the purpose set forth. 115

2. In a reed instrument, the primary channel-board, provided with one opening and channel for each pair of primary pneumatics, and having mounted thereon the music-box 120 and its appliances for playing the instrument automatically, also the keys and connections for playing said instrument by hand; in combination with the series of primary pneumatics, arranged in pairs on said primary channel-board; a cut-off valve, arranged between the pneumatics of each pair; a double wind-chest, provided with separate channels and double, cut-off or switch valves, two of each for each pair of primary pneumatics, and said valves separately connected with said 125 primary pneumatics; a secondary channel-board, provided with two channels for each pair of wind-chest channels, each separately connected with said wind-chest channels, and 130

- a tone-chamber, containing a series of separate, secondary pneumatics and reed-valves, one of each for each primary channel and reed, the channel-board of said tone-chamber being also provided with two, double channels and cut-off valves for each secondary pneumatic, controlled by two "stops" for each tone-chamber, substantially as and for the purpose set forth.
- 5 3. In a reed instrument, the primary channel-board, provided with one opening and channel for each pair of primary pneumatics, and having mounted thereon the music-box and its appliances for playing the instrument automatically; in combination with the series of primary pneumatics, arranged in pairs on said primary channel-board; a cut-off valve, arranged between the pneumatics of each pair; a double wind-chest, provided with se- 10 arate channels and double cut-off or switch valves, two of each for each pair of primary pneumatics, and said valves separately connected with said primary pneumatics; a secondary channel-board, provided with two channels for each pair of wind-chest channels, each separately connected with said wind-chest channels, and a tone-chamber, containing a series of separate, secondary pneumatics and reed-valves, one of each for each primary channel and reed, the channel-board of said tone-chamber being also provided with two, 15 double channels and cut-off valves for each secondary pneumatic, controlled by two "stops," for each tone-chamber, substantially as and for the purpose set forth.
- 10 4. In a reed instrument, the primary channel-board, provided with one opening and channel for each pair of primary pneumatics; a secondary channel-board and a double wind-chest, each provided with double, connecting-channels, and said wind-chest with two, 20 double, cut-off or switch valves for each pair of primary pneumatics, said valves being connected, one with each pneumatic of each pair; in combination with the series of primary pneumatics, arranged in pairs on said primary channel-board, and a cut-off valve arranged between the pneumatics of each pair, substantially as and for the purpose set forth.
- 20 5. In a reed instrument, the primary channel-board, provided with one opening and channel for each pair of primary pneumatics; a secondary channel-board and a double wind-chest, each provided with double, connecting-channels, and said wind-chest with two, 25 double, cut-off or switch valves for each pair of primary pneumatics, said valves being connected, one with each pneumatic of each pair; in combination with the series of primary pneumatics, arranged in pairs on said primary channel-board, and a cut-off valve arranged between the pneumatics of each pair, substantially as and for the purpose set forth.
- 25 6. In a musical instrument, the combination of the primary channel-board, having one channel for each pair of primary pneumatics; with the series of primary pneumatics, arranged in pairs on said primary channel-board, and a cut-off valve, arranged between the pneumatics of each pair, substantially as and for the purpose set forth.
- 30 7. In a musical instrument, the combination of the primary channel-board, having one channel for each pair of primary pneumatics; with the series of primary pneumatics, arranged in pairs on said primary channel-board, and a cut-off valve, arranged between the pneumatics of each pair, substantially as and for the purpose set forth.
- 35 8. In a musical instrument, the combination of the primary channel-board, having one channel for each pair of primary pneumatics; with the series of primary pneumatics, arranged in pairs on said primary channel-board, and a cut-off valve, arranged between the pneumatics of each pair, substantially as and for the purpose set forth.
- 40 9. In a musical instrument, the combination of the primary channel-board, having one channel for each pair of primary pneumatics; with the series of primary pneumatics, arranged in pairs on said primary channel-board, and a cut-off valve, arranged between the pneumatics of each pair, substantially as and for the purpose set forth.
